UNITED STATES PATENT OFFICE.

ADOLPH M. HOLSTEIN, OF SYRACUSE, NEW YORK.

DESIGN FOR A CORNER-PIECE FOR COFFINS AND CASKETS.

46,831.

Specification for Design.

Patented Jan. 5, 1915.

Application filed September 11, 1914. Serial No. 861,317. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Corner-Piece for Coffins and Caskets, of which the following is a specification, reference being had to the accompanying drawing, forming a part hereof.

In the drawing, Figures 1, 2 and 3 are, respectively, side and front elevations and top plan view of my design for a corner piece for coffins and caskets.

This design of corner piece for coffins comprises angularly arranged faces having a central embossed figure 1 at the angle thereof, and ridges along the side edges of the corner piece following in a general way the outline of the central figure. This central figure includes a spherical boss 2 at the lower end of the corner piece, an elongated ovoid convex protuberance 3 above the boss 2 and merging into the top thereof, and a knob 4 above the upper end of the protuber-

ance 3, the boss 2 being of greater diameter than the greatest transverse dimension of the protuberance 3, and the knob 4 being of less diameter than the greatest transverse dimension of the protuberance 3. The spherical boss together with the ovoid protuberance have the appearance of being connected at 5 by a neck, the surface of which merges into the surfaces of said boss and protuberance, and the protuberance 3 and the knob 4 have the appearance of being separated by a shallow depression.

I claim:

The ornamental design for a corner piece for coffins and caskets, substantially as shown and described.

In testimony whereof, I have hereunto signed my name in the presence of two attesting witnesses, at Syracuse, in the county of Onondaga, and State of New York, this 5th day of September, 1914.

ADOLPH M. HOLSTEIN.

Witnesses:

S. DAVIS,
F. B. PICKARD.
